UNITED STATES PATENT OFFICE.

ALEXANDER H. DAVIDSON, OF COLMA, AND SEVERUS SUNDELIUS, OF SAN FRANCISCO,
CALIFORNIA.

CREMATION FURNACE.

1,421,919.

Specification of Letters Patent.

Patented July 4, 1922.

Application filed July 7, 1916. Serial No. 107,924.

To all whom it may concern:

Be it known that we, ALEXANDER H. DAVIDSON, of Colma, California, and SEVERUS SUNDELIUS, of San Francisco, California, 5 have invented certain new and useful Improvements in Cremation Furnaces, whereof the following is a specification.

The invention relates particularly to a crematory having a plurality of combustion 10 chambers that can be operated by one heat unit, means for circulating heated gases through said chambers, means for individually controlling the circulation in each of said chambers; means for consuming smoke 15 arising from the combustion chambers, means to prevent the transmission of vibration from the furnace to the combustion chambers and means to create a supply of heat.

20 The primary object of this invention is to provide a crematory of this nature which shall be highly efficient in operation, which may be easily controlled to direct the heat to any one or all of the combustion chambers 25 at any time required.

With these and other objects in view, the invention aims to generally improve crematories to render them more substantial, practical and commercially desirable.

30 In the drawings:

Figure 1 is a fragmentary horizontal sectional view through a crematory constructed in accordance with our invention.

Figure 2 is a vertical sectional view on the 35 plane of line 2—2 of Figure 1.

Figure 3 is a vertical section on plane of line 3—3 of Figure 2, and

Figure 4 is a similar section on the plane of line 4—4 of Figure 2.

40 Referring in detail to the drawings by numerals, 1 designates as an entirety the crematory which is constructed with the combustion chambers 2, each of which is formed with a top wall 3, a bottom 4, and a 45 rear wall 5. A door 6 slideable in guides 7 closes the front end of each of the combustion chambers. Each of these doors is operated by a flexible connection 8 which extends upwardly over a pulley 9, as shown in Fig-

ure 2, and to any convenient place. The 50 combustion chambers and the furnace are separated by an open joint 10 which is intended to deaden the sound from the burner or other sources.

The open joint 10 prevents vibration of 55 the furnace walls from being conducted through the walls to the combustion chamber walls and hence, acts as a sound deadener and also permits air to be entrained into the combustion chamber. 60

At the rear end of the combustion chambers is the outside wall 12 of the crematory and between these chambers and wall 12 is top 13 and below this top are arranged a series of flues or passages through which the 65 heated gases circulate as will be hereinafter described.

Each of the combustion chambers is formed in its rear wall with a passage 14 closed by a door 15. These passages are 70 found convenient in cleaning the combustion chambers. A main supply passage or flue 16 extends transversely across the rear ends of the combustion chambers 2, and is for the purpose of permitting heated gases or heated 75 air to be supplied to the chambers. Each of said chambers is formed with an inlet port or passage 17 in its rear wall which communicates with the passage 16; thereby establishing a communication between the 80 chamber and the passage. In the front end of each of the combustion chambers and at the bottom thereof is formed an escape or discharge port or passage 18 which communicates with a flue 19 running longitudinally along the bottom of the chamber to a transverse flue 20 and back of the combustion chambers and if desired outside the 85 crematory to above the burner. We have constructed the crematory with two of these 90 flues or passages 20, one being on each side of the transverse center of the structure.

Referring to Figure 3, it will be seen that each of these flues communicates by a vertical passage 21 with a horizontal passage 22 95 running parallel to the corresponding passage 20 but above the same. Each passage 22 which may be placed above the burner if

desired, leads to a flue or passage 23, connecting with a chimney 24, shown in dotted line in Figures 3 and 4. As the crematory is constructed the same on both sides of its longitudinal center, we have not thought it necessary to show the entire construction but have omitted one of the combustion chambers and its associated parts as will be apparent on reference to Fig. 1. A plurality of pipes 25 which form the smoke consuming means extend transversely through each of the passages 22 and open into the adjoining passage 16 causing by this arrangement the smoke and gases arising from the combustion chambers to pass in zig zag between them and by their heated condition destroy all smoke.

To control the flow of hot air or gases into the combustion chambers, we have provided for each chamber a slide plate or door 26 which closes or opens the corresponding port or passage 17. Each of these doors is controlled by a flexible connection 27, which extends upwardly outside of the furnace, as shown in Figures 3 and 4. Another set of doors or slides 28 operated with flexible connections 29 control circulation through the passages 19 shown in the same figures.

Under each of the combustion chambers and in alignment with the passage 18 thereof, we provide a receptacle 30 in which refuse from the combustion chamber may be collected. These pans may be withdrawn through the passage 31 when they are ready for emptying.

In connection with the crematory proper previously described, we provide a heating plant which may be located at any convenient distance from the crematory 32, and which is preferably formed with a fire box 33 into which extend burners 34. The heated air and gases created by this burner circulate through the passage 35 of the fire box to the main inlet passage 36 in the main supply passage 16. When the doors 26 and the doors 28 are opened, the hot gases have a free circulation through the combustion chambers and the flues or passages 19, the flues 20, 22 and 23, to the chimneys. The casket containing a body is supported by the ledges 37, shown in Figure 2, projecting from the sides of a combustion chamber, and it will be seen that the heated gases have a free circulation around the casket to properly incinerate the corpse. 38 indicates a baffle or damper, shown in Figures 1 and 4, which normally cuts off communication between the passage 16 and the flue 23, but when a free passage of the gases direct to the chimney is desired, this damper or baffle is raised.

From the foregoing description taken in connection with the accompanying drawings, it will be apparent that we have provided a very practical and efficient crematory having

a plurality of combustion chambers, each of which is provided with means for controlling the circulation of heated gases thereto, whereby any one of said chambers may be rendered inoperative.

Having thus described our invention and an embodiment of it, in the full, clear and exact terms required by law, and knowing that it comprises novel, useful and valuable improvements in the art to which it pertains, we here state that we do not wish to be limited to the precise construction and arrangement of the several parts, as herein set forth, as the same may be variously modified by a skilled mechanic without departing from the spirit of the invention.

What we claim and desire to secure by Letters Patent of the United States, is the following, to wit:

1. In a crematory, a plurality of combustion chambers, a main supply passage to convey heated gases to said combustion chambers, a furnace connected to said supply passage, said connection being provided with an open joint for preventing the transmission of vibration from the furnace to the combustion chambers and for permitting the entrainment of air into said combustion chambers and said passages being formed each with an escape port, a flue connected with each of said escape ports, and means connecting said flues, and means to convey gases from said connecting means to the atmosphere.

2. A crematory comprising in combination a combustion chamber, a furnace, a main passage between said chamber and the furnace adapted to supply heated air and gases from said furnace to said combustion chamber, an escape port in said combustion chamber, a longitudinal flue connected to said escape port, a transverse flue connected to said longitudinal flue, a vertical passage connected to said transverse flue, a horizontal passage connected to said vertical passage, a plurality of transverse heated pipes in said horizontal passage causing thereby the smoke from the combustion chamber to circulate in zig zag through said passage, a chimney and a longitudinal flue connecting said horizontal passage to said chimney.

3. A crematory comprising in combination a plurality of combustion chambers, a furnace, a main passage adapted to supply heated air and gases from said furnace to said combustion chambers, a second passage communicating at one end with said main passage and at its opposite end with said furnace and provided with an open joint between said furnace and the main passage, said passage being adapted to convey heated air and gases from said furnace to said main passage, an escape port in each of said combustion chambers, longitudinal flues con-

nected to said escape ports, a transverse flue connected to said longitudinal flues, a vertical passage connected to said transverse flue, a horizontal passage connected to said vertical passage, a chimney and a longitudinal flue connecting said horizontal passage to said chimney.

5 In testimony that we claim the foregoing,

we have hereto set our hands in the presence of witnesses this 30 day of June, 1916.

ALEXANDER H. DAVIDSON.
SEVERUS SUNDELIUS.
